DESIGN FOR AN AMALGAM MIXER

Henry E. Meltzer, Racine, Wis.

Application August 1, 1947, Serial No. 140,660

Term of patent 14 years

(Cl. D24—1)

To all whom it may concern:

Be it known that I, Henry E. Meltzer, a citizen of the United States and resident of Racine, county of Racine, and State of Wisconsin, have invented a new, original, and ornamental Design for an Amalgam Mixer, of which the following is a specification, reference being had to the accompanying drawings, forming part thereof.

I claim:

The ornamental design for an amalgam mixer, as shown.

HENRY E. MELTZER.
